COMBINATION QUAD AND PRINTER'S
PLATE REGISTERING HOOKCharles F. Dausmann, Hempstead, N. Y., assignor
of one-half to Fred W. Hoch, Brooklyn, N. Y.

Application July 28, 1933, Serial No. 682,676

4 Claims. (Cl. 101—385)

The invention relates to printers' plate hooks, and more particularly consists of a plate registering quad hook.

Heretofore, plate hooks have been proposed but these were attendant with devices of a rather complicated kind, were required to be applied to diagonally disposed grooves of dovetail and other constructions, and the clamping members were of such width that the spacing margin between the plate and type was entirely too wide for a vast majority of standard printing jobs. Also, such plate-registering members did not permit of a true register as the clamped plates were not movable in true parallelism with the edges of the plates to be registered.

This invention overcomes these objections and provides means whereby the plate may be brought as close to the type as possible, in which the quad holds the hook, the hook holds the plate, and the hook registers the plate, forming thereby a plate registering quad hook. In its embodiment, it contains swivel means to enable the clamping hook to adjust itself to the plate, and is also a close spacing quad hook. It may also be defined as a quad with means for the engaging plate, or a quad with adjustable means for engaging the plate.

The invention will be more fully described hereinafter and embodiments shown in the drawings, and the invention will be finally set forth in the claims.

In the accompanying drawings:—

Figure 1 is a plan view of a plate held in registration by my improved hook and surrounded by type, all held together in a chase;

Figure 2 is a vertical transverse section taken on the line 2—2 of Figure 1;

Figure 3 is a plan view of the improved hook showing various positions in dotted lines;

Figure 4 is a central section taken on the line 4—4 of Figure 3;

Figure 5 is a perspective view of the improved quad;

Figure 6 is a perspective view of the hook itself taken out of the quad shown in Fig. 5;

Figure 7 is a perspective view of the key used for adjusting the hook in the quad;

Figure 8 is a plan view of the improved adjustable hook specially adapted to narrow spaces between the plate and the type;

Figure 9 is a sectional view taken on the line 13—13 of Figure 8;

Figure 10 is a plan view of the improved adjustable hook shown in Figures 8 and 9;

Figure 11 is a perspective view of another form

of the quad shank constructed according to the principle of the quad shown in Figure 5, but having a circular contour;

Figure 12 is a perspective view of a quad having a circular bore adapted to receive the circular contour of the quad shank of Figure 11; and

Figure 13 is a perspective view of the hook shown in Figures 8 to 10 and adapted to fit into the quad shank portions shown in Figure 11.

Similar reference characters indicate corresponding parts throughout the various views.

Referring to the drawings, and more particularly to Figures 1 to 7, the well-known chase 20 is provided with quoins 21 which hold furniture 27 and printing type 23. Within the space 15 bounded by the inner portions of the printing type, quads 28 are arranged and to certain of these quads, printers' plate registering hooks are attached, these being indicated by 30 having an opening 31 for the insertion of a key 48 having 20 a stem 44 with handle 49 as shown in Figure 7. These plate hooks engage the exterior contour of an electrotype or half tone plate 25 and hold the same in position in respect to the type. In addition to the furniture 27, suitable spacing blocks 25 may be inserted in a manner well known in the printers' art.

There has been considerable difficulty in the registration of plates in respect to the type in proximity thereto, and the improved plate hook 30 more particularly to be described overcomes these objections.

The invention provides a plurality of quads 28 as shown in Figure 2, these quads being generally blocks of lead or the like suitably spaced adjacent to each other so that the entire plurality of blocks takes up the necessary space within the printers' chase. Certain of these quads are provided with openings and within these openings printers' plate hooks are adjustable so as to adjust themselves to the alignment of the exterior contour of the plate to be registered. Referring more particularly to Figures 3 to 6, the special quads suitably distributed among the other quads forming the background of the plate is shown in 45 the perspective view of Figure 5, in which two parallel side walls 35 are each provided with horizontal grooves 36 and with an inclined bottom 37. The plate hook itself consists of a cylindrical portion 38 as shown in Figure 6, having integral 50 therewith a cross bar 32 with an inclined side 34. At the lower part of the cylindrical portion 38, extending flanges 47 are provided which extend beyond the cylindrical portion 38, while at right angles thereto, flat portions 46 at either side of 55

the member 38 are arranged flush with the contour of the member 38. Within the member 38, interior screw-threads 40 are provided and within these screw-threads, a screw-threaded member 39 may be moved in and out of the cylindrical portion 38. The screw-threaded member 39 has an angular recess 43 engageable by the registering angular stem 44 of the key 48. The lowermost portion of the screw-threaded member 39 is circular or curved which provides a satisfactory riding surface upon the inclined bottom 37 of the quad. The member 38, as also its cross bar 32, is provided with a central bore 42, having an opening 31, and this permits the passage of the adjusting key so as to engage with the screw-threaded portion 39. The flanges 47 are adapted to seat within the recesses 36 of the quad. When these flanges 47 seat in these recesses 36, the hook may be moved to and fro within the quad by applying suitable rotary pressure to the screw-threaded portion 39 and riding the same up or down the inclined surface 36. It will be clear that a certain amount of angular adjustment is possible by shifting the cross bar 32 which has its two oppositely disposed angular surfaces 33 and 34 in an angular direction, as shown in dotted lines in Figure 3, the degree of angular adjustment being determined by the retention of engagement between the flange 47 and the recesses 36 of the quad. When, however, the cross bar 32 is moved so as to be in line with the opening between the two side walls 35, whereby the flanges 47 disengage from the recesses, and the parallel surfaces 46 are flush with the interior walls of the parts 35, then the hook may be freely taken out of the quad. It may also be removed from the quad by moving the members 38 in a direction parallel with the sides 35 until the flanges 47 ride out of the recesses, but a more convenient form of removal is by turning the hook so as to remove any engagement between the flanges 47 and the recesses. When the adjusting key shown in Figure 7 is applied to the opening 31 of Figure 6 and the screw-threaded member 39 is moved, the upper surface 45 of the flanges 47 engage against the upper wall of the recesses 36 and a locking action fixing the hook in position to the plate is then provided.

It will be seen by the use of this improved quad, a cross bar may be held in its proper position of registration in respect to the surrounding type by adjusting the hook into proper angular position and holding it thereby to the base by the application of the locking force through the instrumentality of the adjusting key.

It will also be noted that the cross bar 32 has two angular walls 33 and 34. The reason for these walls is that the cross bar may be turned around 180 degrees and by this the cross bar is nearer or further away from one side of the quad. Depending upon the relation of the exterior contour of the plate to the adjacent type, either of these two positions is selected, depending upon the special circumstances applicable.

The embodiment shown in Figs. 8 to 10 provides an angularly adjustable narrow hook. Here the cross bar 63 is provided with angular surfaces, and this cross bar has an opening 64 to enable the key to be inserted therein, this opening being made especially small and the key correspondingly small in diameter. By this very narrow construction of the cross bar 63 an angular adjustment is permitted in the manner as heretofore described in connection with Figure 3, and the advantages of an adjustable hook are provided.

If the cross bar be made still narrower, then such an embodiment would not have the advantage of the 180 degrees transposition of the cross bar 32 of Figure 3.

This embodiment of the invention is further shown in Figures 11 to 13, in which the quad 61 of rectangular shape is provided with a central bore 62. This bore, while shown centrally, is axially disposed. Within this bore 62 a supplementary quad or quad shank member is inserted. This member consists of two parallel walls 66, having lateral recesses 67 and an inclined bottom 68. This supplementary quad shank 65 is inserted into the bore 62 of the quad 61. Within the supplementary quad member 65, the adjustable hook 69 is insertable, having the flanges 70 and the screw-threaded portion 71 with the narrow cross bar 63 and the opening 64 for the key 48.

It will be seen from the foregoing, that the improved printers' plate registering hook consists particularly of a plate registering quad hook having the advantage of being readily placed in any portion of the base along the contour of the plate to be registered, and having the further advantage of taking up very little space between the plate and the type, and finally the advantage of being adjustable angularly so as to adapt itself to any angular position of the plate. I have shown various embodiments of my invention, and changes may be made in the details thereof without departing from the spirit of my invention as defined by the appended claims.

I claim:—

1. A registering hook comprising a quad having a space the bottom of which is inclined to the horizontal, said quad having a substantially horizontal channel on each side of the space above the bottom, a substantially vertically disposed quad shank, opposed flanges secured to the shank and slideable in said channels, said shank having a threaded bore therein inclined to the vertical with the angle of the inclination oblique to the plane of the bottom, a quad shank adjusting member disposed in the bore of the shank and provided with a lower end engageable with said bottom, and a hook on the upper end of the shank.

2. A registering hook comprising a quad having a space the bottom of which is inclined to the horizontal, said quad having a substantially horizontal channel on each side of the space above the bottom, a substantially vertically disposed quad shank having the top thereof flush with the top of the quad, opposed flanges secured to the shank and slideable in said channels, said shank having a threaded bore therein inclined to the vertical with the angle of the inclination oblique to the plane of the bottom, a quad shank adjusting member disposed in the bore of the shank and provided with a convex lower end engageable with said bottom, and a hook on the upper end of the shank.

3. A registering hook comprising a quad having a space the bottom of which is inclined to the horizontal, said quad having a substantially horizontal channel on each side of the space above the bottom, a substantially vertically disposed quad shank having the top thereof flush with the top of the quad, opposed flanges secured to the shank and slideable in said channels, said shank having a threaded bore therein inclined to the vertical with the angle of the inclination oblique to the plane of the bottom, a quad shank adjusting member disposed in the bore of the shank and provided with a lower end

engageable with said bottom, and a hook on the upper end of the shank and disposed at one side of the center thereof whereby the plate engaged by the hook rests on the remaining portion of the top of the shank.

5. A registering hook comprising a quad having a space the bottom of which is inclined to the horizontal, said quad having a substantially horizontal channel on each side of the space above the bottom, a substantially vertically disposed quad shank, opposed flanges secured to the shank and slideable in said channels, said shank having a

threaded bore therein inclined to the vertical with the angle of the inclination oblique to the plane of the bottom, a quad shank adjusting member disposed in the bore of the shank and provided with a lower end engageable with said inclined bottom, and a hook jaw on the upper end of the shank, said opposed flanges being so shaped as to retain engagement with the channels, when said hook jaw is disposed angularly to the channels.
